UNITED STATES PATENT OFFICE

JOHN J. JAKOSKY, OF LOS ANGELES, CALIFORNIA, ASSIGNOR TO INTERNATIONAL PRECIPITATION COMPANY, OF LOS ANGELES, CALIFORNIA, A CORPORATION OF CALIFORNIA

PHONOGRAPH REPRODUCER

Application filed September 15, 1926. Serial No. 135,504.

This invention relates to apparatus for the reproduction of music or other sounds from a phonograph record and the principal object of the invention is to provide an apparatus for this purpose which gives a better quality 5 of reproduction than has heretofore been obtained by any mechanical reproducing device and associated horn.

A further object of the invention is to provide 10 a reproducing device which is simple in construction and operation, and which eliminates the necessity for the horn ordinarily employed for amplifying and modulating the sound produced by the phonograph diaphragm.

A further object of the invention is to provide 15 a reproducing device which may be easily attached to an existing phonograph so as to provide for increased quality of reproduction.

A further object of the invention is to provide for perfect and uniform reproduction of all sounds recorded on a phonograph record, while preventing to a large extent the production 20 of foreign noises, such as the "scratching" sound ordinarily present in phonographic reproduction.

In the ordinary type of mechanically reproducing phonographs heretofore used, it 25 has been customary to employ a vibrating diaphragm of relatively small area and to direct the sound waves produced by the vibration of such diaphragm into and through a gradually expanding horn, whereby the 30 sound waves were amplified and the quality of sound improved. If the horn be removed from such a reproducer, the sound produced by the diaphragm is not only poor in volume, but is also lacking in quality and richness. In 35 a reproducer of this type, it has been found that the air chamber opposite the diaphragm, which directs the sound waves from the diaphragm into the base of the horn, should not exceed a certain volume, owing to compression 40 of air therein and resonance effects, and this in turn limits the area of diaphragm which may be employed. It has therefore been found necessary, in order to increase the 45 volume and quality of reproduction, to increase the length of the horn, and it has been

found that the use of properly designed and proportioned horns of increased length does increase the volume of sound produced and usually also the range of frequencies of sound which may be produced. The provision of a 55 horn of such great length, however, seems to muffle and distort the sound, so that the resulting sound is not a true reproduction of the sound from which the record was made. Furthermore, the sound emanating from a 60 horn of this type is quite directional, that is, it appears to come only from the direction of the horn, and is much more loud and distinct directly in front of the horn than at either side or in back of the same. Another objection to reproducers of this type is that the 65 diaphragms employed have a natural period of vibration and that they are much more readily responsive to vibrations of certain frequencies than others. The first of these 70 facts causes "blasting" or greatly increased loudness at sounds within a frequency band approximating the resonant frequency of the diaphragm, while the second causes non-uniformity of reproduction of sounds of varying 75 pitch.

The same disadvantages and objections have been encountered in the designing of loud speakers for radio reception and other purposes, but in this latter field they have 80 been eliminated or largely overcome by the use of substantially aperiodic diaphragms or membranes, thus eliminating "blasting" and non-uniformity of reproduction, and by making the diaphragm or membrane of such area 85 that it will produce directly, without the use of a horn, sound of the desired volume and quality. Such membranes may be made of any desired size depending upon the volume 90 of sound desired. Furthermore, the sound produced thereby is substantially non-directional, that is, it appears to travel outwardly in all directions from the loud speaker, so that it gives the effect of emanating from the 95 whole room instead of from a single point and may be heard practically equally well from all points at equal distances from the source.

According to my invention a diaphragm 100 or membrane of this latter type is adapted

for use in phonographic reproduction, that is, a membrane which is substantially aperiodic and of sufficient area to produce directly without the use of an amplifying horn, sound of sufficient volume for pleasing reproduction in an ordinary size room, it being understood that the size of the membrane may be made large enough to produce sound of almost any desired volume. While I do not wish to be limited to any specific area or size of membrane, it is in general necessary to employ, for the purposes above mentioned, a membrane having an effective area of about 28 square inches or more and my invention 10 may therefore be understood as contemplating the use of a membrane having an area of not less than this amount. The optimum size of the membrane will depend in any particular case upon the length of lever arms involved in the operating mechanism, and upon other mechanical factors, as well as upon the volume of reproduction desired. For general purposes, however, a membrane of from ten to fourteen inches diameter may 20 usually be advantageously employed. As in the case of radio loud speakers, the use of such a membrane, without a horn, in a phonograph reproducer does away with "blasting," gives uniform reproduction of sound 25 throughout a wide range of pitch, permits any desired volume to be obtained without distortion or muffling, and causes the sound to be more uniformly distributed in all directions instead of emanating from one point 30 and in substantially one direction only.

The invention comprises essentially a substantially aperiodic vibratory membrane of sufficient area to produce the desired volume of sound without necessitating an amplifying horn, and means for supporting said membrane in such manner as to permit substantially free radiation of sound waves therefrom and for causing the same to be vibrated or actuated in response to the vibrations imparted to a phonograph needle by the undulations in a phonograph record. The invention further comprises the use of aperiodic supporting and damping means in connection with the mechanism for transmitting 40 the vibrations of the needle to the vibratory membrane. Other features of the invention include adjustable damping means for regulating the amplitude of vibration of the membrane and hence regulating the volume of 45 sound, and also counterbalancing means in connection with the supporting means for the reproducer so that the weight carried by the phonograph needle is suitably reduced in order to prevent too great a pressure of 50 such needle against the grooves of the record.

A further feature of the invention consists in the provision of a rocking member having means for carrying a phonograph needle, means supporting the rocking member so as to permit relatively free rocking 55

movement thereof about one axis, due to vibrations imparted to the needle by the recorded undulations on the record, but to relatively restrict rocking movement thereof in another direction as well as translative motion thereof due to accidental vibrations of the phonograph needle, and means connecting the rocking member to the vibratory membrane in such manner that rocking movement of the member in the first-named 70 direction is effectively transmitted to the membrane, while any rocking movement which may occur in the second named direction is not substantially so transmitted.

The accompanying drawings illustrate 80 embodiments of my invention and referring thereto:

Fig. 1 is a vertical section of the reproducing device.

Fig. 2 is a partial horizontal section on line 2—2 in Fig. 1.

Fig. 3 is a section on line 3—3 in Fig. 2.

Fig. 4 is a section on line 4—4 in Fig. 2.

Fig. 5 is a section on line 5—5 in Fig. 1.

Fig. 6 is a vertical section of a modified 90 form of the invention.

In Fig. 1 part of an ordinary phonograph cabinet is indicated at 1, within which is mounted a phonograph motor 2 of any suitable type, either electrical or spring-driven. 95 The shaft 3 of said motor projects through the cabinet and is provided with the usual disc-shaped plate 4 for carrying and rotating the phonograph record indicated at 5. The phonograph is further understood as being provided with the usual means for stopping and starting motor 2, for regulating the speed thereof, and for winding in case of a spring-driven motor.

The reproducing device comprises a vibratory membrane 7 of suitable aperiodic material such as paper formed in the general shape of a double cone, that is to say two cones 8 and 9 joined together at their bases as at 10. As shown, however, the lower cone 9 is preferably somewhat truncated and a supporting plate 12 may be mounted so as to extend across, or partly across the opening thus afforded, said supporting plate being secured to the lower edge of cone 9, for example by means of ring 13. In the case of a double cone supported in this manner, the effective area of the membrane may be considered as substantially the area of the upper cone, or in general the area of the cone to which the operating mechanism is connected. The lower cone, while it undoubtedly does produce some sound, serves mainly to flexibly support the upper cone.

The reproducing device may be mounted at the outer end of supporting arm 14 which is secured for example to the supporting plate 12, said arm being pivotally mounted at its other end on pivot 15 mounted on yoke 16. Said yoke is mounted so as to swing hori- 125

zontally as by means of pivotal supports 17 on a supporting bracket 18 mounted in a suitable position on the phonograph cabinet. A counterweight 20 may be mounted on counter-weight arm 21 which is also pivoted on pivot 15 so as to permit movement of the arm 14 independently of the counterweight under certain conditions. The counter-weight arm 21 may be provided with a shoulder or abutting portion 22 adapted to be engaged by shoulder portion 23 on supporting arm 14 when the reproducing device is lowered into playing position as shown in Fig. 1 so that when in this position, the counterweight is in effective counterbalancing position. When however the reproducing device is tilted upwardly to the position indicated in dotted lines at 25 for the purpose of changing the phonograph record or inserting a new needle 15 in the device, supporting arm 14 moves away from engagement with shoulder 22 so that the counterweight is allowed to fall slightly until shoulder 22 comes into engagement with the vertical portions of yoke 16 so that at 25 this time the reproducing device is permitted to swing vertically independently of the counterweight. A handle 26 may also be secured to the supporting plate and may extend forwardly beneath the vibratory membrane 8, into a position in which it may be easily grasped for lifting the reproducing device off the record.

A substantially rigid rocking member or lever member 27 may be mounted between aperiodic supporting and damping members such as rubber pads 28, there being one of such rubber pads below and one above each end of the lever member 27, and said supporting means being held in position to support said lever member by means of clamping plates or straps 29 secured to supporting plate 12. The rocking member 27 may be provided with a needle-carrying member 30 which may be integrally formed therewith or rigidly secured thereto in any suitable manner, said needle-carrying member being adapted to receive and hold an ordinary phonograph needle or stylus 24 at a suitable inclination to the face of the record, in the usual manner of such devices and being provided with a retaining screw 31 for holding the needle in position therein. The needle-carrying member 30 is preferably mounted substantially on the axis about which the rocking member 27 is adapted to rock or vibrate, which axis is substantially the longitudinal mid-line of such rocking member or the line joining the mid-points of the supporting and damping means therefor as indicated at $x-x$ in Fig. 2. As clearly shown in Fig. 2, this axis of vibration lies in the plane of the needle 24.

Auxiliary damping means are preferably provided so as to permit an adjustment of the degree of damping to which the rocking

or vibrating member 27 is subjected. For this purpose said rocking member may be provided with a laterally projecting arm 33 and said arm may be held between two resilient aperiodic damping members such as rubber pads 34 which are in turn held in place between adjustable clamping arms 35. Said clamping arms may be mounted as at 36 on the supporting plate 12 and an adjusting screw 37 may be provided which has reverse- 70
ly threaded portions adapted to engage respectively in the upper and lower clamping plates 35 so that turning of said adjusting screw in one direction serves to draw the clamping plates closer together and increase 75 the damping action while turning of said screw in the other direction serves to spread the clamping plates further apart and decrease the damping action.

A translating member such as a light flexible wire indicated at 38 may be connected at one end to the rocking member 27 as indicated at 39 and at the other end to the apex of the upper cone 8 of the vibratory membrane 7. By reason of the flexibility of such translating member it is practically incapable of transmitting motion in any other direction than longitudinally with respect to itself. In order to provide for relative adjustment between the vibratory membrane and rocking member 27, the wire 38 may be adjustably connected to the membrane and for this purpose said wire may extend through sleeve 40 secured to the membrane and a set screw 41 may be provided for holding the wire in any desired position in which it may be set with respect to sleeve 40.

In the operation of the above-described reproducing device for reproduction of music or other recorded sounds from a phonograph record it will be understood that the record 5 is placed on the carrying plate and the same is set in rotation by operation of the motor 2 in the usual manner of such devices. The reproducing device is then lowered onto the record in such manner as to bring the needle indicated at 24 into engagement with the initial groove of the record and such needle is thereby caused to traverse the grooves of the record. The passage of the needle over the undulations of the record causes the same to vibrate in a direction corresponding to the direction of cut of such undulations. The particular form of mechanism shown is adapted for use with records in which the direction of cut is horizontal and transverse to the grooves of the record so that the vibrating member 27 together with the needle carrying member secured thereto is caused to rock or vibrate in a substantially vertical plane about the axis $x-x$ above referred to. Because of the substantially aperiodic nature of the rubber supporting pads 28 and the rubber damping pads 34, such rocking movement of member 27 is substantially aperiodic, that 130

is, such member is substantially equally susceptible to vibration at frequencies of a wide range. It will be seen that since the point of connection 39 of wire 38 to rocking member 37 is horizontally spaced from the axis $x-x$, the wire or translating member 38 will be caused to move alternately up and down in response to the rocking movement of member 27 and will therefore cause the vibratory membrane 7, including both the upper and lower cones 8 and 9, to vibrate at a frequency corresponding to the frequency of the sound recorded on the record. The amplitude of vibration of the vibratory membrane will be proportional to the amplitude of the undulations in the record and will also depend upon the ratio of the relative distance of the needle point and point 39 from the axis $x-x$. Such amplitude also depends upon the amount of damping action exerted by the resilient pads 34, and it will be seen that by adjusting screw 37 the amplitude of vibration may be adjusted within wide limits. The resulting vibration of vibratory membrane 7 causes sound waves to be produced which correspond faithfully in frequency and relative intensity to the sound recorded on the record. Due to the aperiodic nature of such membrane it is substantially equally susceptible to vibrations of widely varying frequency, and there is no tendency for the same to oscillate or "blast" at frequencies corresponding to sounds of certain pitch as is the case with the usual type of diaphragm employed in phonograph reproducers. Furthermore, the sound produced by the vibrating membrane does not pass through any horn and is consequently permitted to radiate or travel outwardly uniformly in all directions. The sound therefore gives the effect of simply filling the room rather than emanating from one certain point in the room as was the case with the horn type reproducer.

It will be seen that any accidental vibration imparted to the phonograph needle in a direction other than the cut of the record, will be much less effectively transmitted to the vibratory membrane than are the vibrations in the direction of such cut. For example, vibration of such needle in a vertical plane would tend to move the rocking member bodily up and down or rock it about the horizontal axis $Y-Y$ (Fig. 2).

Both of these motions of the rocking member are, however, substantially prevented or relatively restricted as compared with the rocking motion about axis $x-x$ due to the relatively large distance between the supporting pads 28 in a direction perpendicular to axis $Y-Y$. Furthermore, any rocking motion which may occur about axis $Y-Y$ is not appreciably transmitted to vibratory membrane 8, due to the fact that the point of connection of link member 38 to rocking member 27 is substantially on such axis.

Another modification of the invention is illustrated in Fig. 6. In this form of the invention the vibrating membrane 7 comprises as shown a single cone of light material such as paper or parchment which is free at its outer edge and is secured at its base or center to a rigid pin or translating member 38 which as before is connected to rocking member 27 at a point spaced from the effective axis thereof. Such cone preferably has an area as above defined. A supporting plate 12 is provided in this case as before and it will be understood that such supporting plate may be mounted at the outer end of a supporting arm similar to that above described or may be suitably supported in any desired manner. In this case however the rocking member 27 together with the aperiodic supporting pads 28 therefor and the damping means 34 to 37 inclusive are mounted below instead of above the supporting plate and a cover plate 43 may be secured to supporting plate 12 and extend beneath the rocking member and the supporting and damping means therefor so as to protect the same and conceal them from view. In order to protect and conceal the vibrating membrane 7, a housing frame 44 may be connected by means of radial arms 45 to supporting plate 12 and suitable porous fabric such as wire screen or silk indicated at 46 and 47 may be mounted on said housing frame respectively below and above the vibrating cone 7, so as to permit free passage of sound therethrough while protecting and concealing said cone.

The operation of this form of the invention is substantially the same as that above described with the exception that in this case the vibrating membrane 7 moves up and down bodily in response to motion imparted to link member 38 in the manner aforesaid. Since said membrane is of very light weight and is free at its outer edges, its motion is substantially aperiodic and the same advantages of faithful reproduction of sounds of varying frequency are therefore realized. The porous fabric at 46 and 47 is sufficiently open to permit substantially free radiation of sound waves from membrane 7, while serving to protect said membrane from injury.

I claim:

1. An apparatus for reproducing sound from phonograph records comprising a supporting plate, a vibratory membrane mounted on said supporting plate and formed of such material and of such size as to be substantially aperiodic, a rocking member disposed in a plane substantially parallel to said supporting plate and spaced therefrom and provided with needle holding means adapted to hold a needle in a plane substantially perpendicular to said rocking member, aperiodic resilient means supporting said rocking member on said supporting plate and so disposed as to permit rocking movement

of said rocking member about an axis lying substantially at the intersection of the plane of said rocking member and said perpendicular plane in which the needle is disposed 5 while substantially preventing motion of said rocking member about an axis perpendicular to said first named axis and lying substantially in the plane of said rocking member, and link means connected at one end to said 10 rocking member at a point spaced from said first named axis and substantially in the line of said axis perpendicular to said first named axis, said link means extending substantially perpendicular to said rocking member and 15 being connected at its other end to said aperiodic vibratory membrane.

2. An apparatus as set forth in claim 1, said aperiodic resilient means comprising pads of aperiodic resilient material held in 20 position between said rocking member and said supporting plate and spaced from one another along said first named axis and at opposite sides of said second named axis, and pads of aperiodic resilient material held in 25 tight engagement with the other side of said rocking member and at substantially the same relative positions as said first named pads with respect to said axes.

3. An apparatus as set forth in claim 1, 30 said rocking member being provided with an arm projecting therefrom at the opposite side of said first named axis from the point of connection of said link means, and said apparatus further comprising aperiodic resilient means embracing said arm and means for 35 adjusting the compression of said last named aperiodic resilient means so as to control the damping effect thereof on said rocking member.

40 In testimony whereof I have hereunto subscribed my name this 8th day of September, 1926.

JOHN J. JAKOSKY.
